UNITED STATES PATENT OFFICE.

FREDERICK L. WHIITE, OF WATERBURY, CONNECTICUT, ASSIGNOR, BY MESNE ASSIGNMENTS, TO THE CALCIUM KING LAMP COMPANY, OF SAME PLACE.

DESIGN FOR A BICYCLE-LAMP.

SPECIFICATION forming part of Design No. 29,269, dated August 23, 1898.

Application filed June 20, 1898. Serial No. 684,011. Term of patent 14 years.

To all whom it may concern:

Be it known that I, FREDERICK L. WHITE, a citizen of the United States, residing at Waterbury, in the county of New Haven and State 5 of Connecticut, have invented and produced a certain new and original Design for Bicycle-Lamps, of which the following is a specification, reference being had therein to the accompanying drawings, forming part thereof,

in which—

Figure 1 is a side elevation of a bicycle-lamp embodying my new design. Fig. 2 is a front elevation of the same.

My invention relates to a design for a bicycle-lamp, such lamp consisting of a lamp-body and reflector.

The leading feature of my design is a bicycle-lamp having a body of cylindrical form with rounded ends and a reflector with flaring

sides projecting laterally therefrom and having a smoke hood or cowl upon its top side.

In the drawings the numeral 1 designates the lamp-body having the form of an upright cylinder, both ends of which are rounded; 2, the central band, to which is attached the 25 bracket-arm 3; 4, the reflector; 5, the smoke-hood; 6, the lens in the front of the reflector, and 7 the jewel side light for the reflector.

What I claim is—

The design for a bicycle-lamp, substantially 30 as shown and described.

In testimony whereof I affix my signature in presence of two witnesses.

FREDERICK L. WHIITE.
